PROTECTIVE ARRANGEMENT

Filed June 27, 1928

Inventor:
Richard E. Cordray,
by Charles T. Tullar.
His Attorney.

UNITED STATES PATENT OFFICE.

RICHARD E. CORDRAY, OF SCHENECTADY, NEW YORK, ASSIGNOR TO GENERAL ELECTRIC COMPANY, A CORPORATION OF NEW YORK.

PROTECTIVE ARRANGEMENT.

Application filed June 27, 1928. Serial No. 288,719.

My invention relates to improvements in protective arrangements for electric circuits and more particularly to differential protective arrangements for three or more either 5 conductively or inductively related circuits of which any two of at least three are so arranged as to supply the rest. In differential protective arrangements, particularly such as embody auxiliary transformers and especially current transformers, differences between characteristics of the transformers as 10 actually manufactured from an economical and practical standpoint, although unnecessary to consider for normal load conditions, 15 become greatly exaggerated in accordance with the severity of faults. Consequently, in case of through faults, that is faults outside of the zone of protection to be considered, apparent differences may exist and effect erroneous operation and therefore interrupt the 20 much desired continuity of service. Due to the rapid growth of the interconnection of power systems whereby large blocks of power are available to feed a fault, conditions of 25 this kind frequently appear, for example where the circuits of two or more systems are connected to a transformer having three or more windings or where the circuits of three or more sources are connected to a common 30 bus. In such cases, any source or any two or more sources may feed the rest so that the direction of power as regards input and output may vary greatly although neglecting losses and assuming no fault conditions, the 35 input and output are equal. Of course, if an attempt is made to overcome the difficulty due to the lack of balance in the characteristics of the transformers as practically constructed, by giving higher settings to the fault 40 responsive apparatus such as relays and the like, the sensitivity of protection is sacrificed. In some cases, the power transformer may be provided with a voltage regulating means which, when off the zero position, upsets the 45 balance of the current transformers to the extent of the percentage of voltage regulation employed. This further accentuates the difficulty of correlating sensitivity and continuity of service. An object of my invention 50 is to provide for three or more circuits of which any two of at least three are so arranged so as to be able to supply the rest, an improved protective arrangement whereby to obtain maximum sensitivity and yet avoid 55 erroneous operation on faults outside the protected zone. A further object of my invention is to provide an improved protective arrangement in which the operation of the protective apparatus is based on a predetermined ratio of unbalance between corresponding 60 electrical quantities of the three or more circuits to be protected and not on a mere difference between one of said quantities and a function of the remainder. Other objects of my invention will appear hereinafter. 65

My invention will be better understood from the following description when considered in connection with the accompanying drawing and its scope will be pointed out in the appended claims. 70

In the accompanying drawing, Fig. 1 illustrates partly in diagram and partly in perspective, a protective arrangement for three inductively related circuits shown in single phase for clearness; Fig. 2 illustrates diagrammatically an arrangement similar to Fig. 1 for four inductively related circuits; and Fig. 3 illustrates diagrammatically an arrangement similar to Fig. 1 for three conductively related circuits. 75

In the embodiment of my invention shown in Fig. 1, a plurality of circuits 4, 5, 6 are inductively related, as shown, by being connected respectively to the mutually inductive windings 7, 8, 9 of a power transformer 10. 80 This may be arranged for voltage regulation, schematically indicated by the adjustable lead to the winding 7. Each of the circuits 4, 5, 6 is arranged to be connected to a system including a source of power, not shown, through suitable circuit controlling means indicated as 85 circuit breakers 11, 12, 13 of the latched-closed type, each having a trip coil 14. To one of the windings of the transformer 10, there may in some cases be connected only a synchronous 90 condenser. Such a device, however, may in case of a fault act as a source of power since it tends to operate inverted and feed its stored energy to the fault. In any event, it is possible for any one of the circuits 4, 95 5, 6 to supply the others, any two to supply the third or all three to supply a fault within the transformer 10. Obviously, the relative directions of power may vary greatly even during normal conditions and also on 100 through faults, that is those occurring outside of the transformer or the zone to be protected between the circuit breakers. However, un-

der normal conditions as well as on through faults, the power fed to the transformer 10 is, neglecting losses, equal to the power taken therefrom. This balance is disturbed on the 5 occurrence of a fault within the transformer.

In order to obtain maximum sensitivity and yet prevent unnecessary interruptions of service, I provide in accordance with my invention means for controlling one or more 10 of the circuits 4, 5, 6 through an operating effect which is dependent on the difference between the input and output currents of the circuits and cumulative restraining effects dependent on the circuit currents but independent 15 of the relative directions of power, that is, dependent on only the magnitudes of the circuit currents. The means, which I have illustrated, is of the differential type and includes an electroresponsive device such 20 as a protective relay 15 having an operating winding 16 connected to be energized in accordance with the difference between the input and output currents of the circuits 4, 5, 6 and a plurality of restraining windings 17, 25 18, 19 respectively connected to be energized in accordance with the circuit currents. For this purpose, I may employ a differential protective circuit of the circulating current type. As shown, this circuit includes current 30 transformers 20, 21, 22 respectively associated with the circuits 4, 5, 6. The restraining windings 17, 18, 19 are connected in series with the current transformers 20, 21, 22 respectively and to a common point 23 35 between which and another point 24 normally at the same potential, the operating winding 16 is connected. In order to use standard current transformers and yet allow for the turn ratios of the power transformer 40 10 and the voltage regulation thereof suitable means such as one or more adjustable auto-transformers 25, 26 may be provided. With this arrangement each of the restraining windings 17, 18, 19 will be energized by 45 a current proportional to the current in the circuit with which its respective current transformer is associated and the operating winding 16 will be energized by a current dependent on the difference between the input 50 and output currents of the circuits 4, 5, 6.

The relay 15 may be of the induction disk type and as illustrated includes a movable member such as the contact controlling arm 27 secured to a shaft 28 on which are mounted 55 one or more disks 29, 30 of electric current conducting material. In order to control the movable member by the effect of the operating winding 16 as opposed to the cumulative defects of the restraining windings 17, 18, 19, 60 these windings may be respectively applied to shaded pole motor elements 31, 32, 33, 34 inductively associated with the disks 29, 30, two disks being preferably employed in order to avoid the possibility of magnetic interference 65 between the elements. The three re-

straining elements 32, 33 and 34 are arranged to exert cumulative torques on the disks 29, 30 so that each tends to turn and hold the circuit controlling arm 27 against a stop 35, the direction of their torques being indicated 70 by the arrows 36. The operating motor element 31 exerts a torque in the opposite direction tending to move the circuit controlling arm 27 to circuit closing position. Since the direction of the torque of a shaded pole 75 motor element on its associated conducting disk is dependent only on the positioning of the short-circuited or shading winding, the directions of the torques exerted by the motor elements 31, 32, 33, 34 are independent 80 of the directions of the currents in the windings 16, 17, 18 and 19 and, therefore, of the relative directions of power in the circuits 4, 5, 6.

The expression for the resultant torque, T , 85 for moving the circuit controlling arm 27 is therefore:

$$T = (I_1^2 + I_2^2 + \dots + I_n^2) - (I_s - I_t)^2$$

where $I_1, I_2, \dots, I_n$ represent the currents 90 in the respective circuits, n being the number of circuits I_s and I_t represent the sum of the currents supplied by and taken from the circuits 4, 5, and 6. Where a plurality of circuit breakers 11, 12, 13 are to be controlled 95 it is preferable in order to avoid severe duty on the contacts of the sensitive protective relay 15 to have it control an intermediate or auxiliary device such as a relay 37 which is arranged to control the circuits of the trip 100 coils 14. In accordance with my invention I preferably base the operation of the relay 15 not on the mere difference between the effect on the operating winding 16 and the combined cumulative effects of the restraining 105 windings 17, 18, 19 but on a predetermined ratio between these effects. This may be done by suitably proportioning the turns of the operating winding 16 to the turns of the restraining windings 17, 18, 19 so that 110 tripping is effected only when the ratio between the effects exerted by the operating and restraining windings exceeds a predetermined value. Then on through faults which cause heavy currents, the same relay balance 115 is maintained and even though current transformer characteristics may vary considerably, the relay 15 can be set to maintain itself ineffective to trip until a fault occurs in the zone which it is intended to protect. In fact 120 this ratio balance action may be such as to permit considerable variation in the voltage of the power transformer 10 when a voltage regulating unit is associated therewith.

Assuming a through fault on the circuit 5, 125 that is beyond the circuit breaker 12, then both of the circuits 4 and 6 will feed the fault but the input and output currents of the circuits remain substantially equal so that the points 23 and 24 should be at the same potential. 130

Under these conditions no current appears in the operating winding 16. The restraining windings 17, 18, 19 will be energized by currents proportional to those appearing in the 5 circuits 4, 5, 6 and the total restraining effect is the sum of the torques due to these windings. While there theoretically exists no difference between the input and output currents such difference actually does appear in 10 case of severe through faults due to unbalance in current transformer characteristics. This apparent difference, however, is insufficient to overcome the restraint due to the effect of the restraining windings 17, 18 and 15 19. This, it will be apparent, is always the case no matter what two circuits feed a faulty circuit or whether one circuit happens to feed two circuits simultaneously at fault. In case of internal faults on the power transformer 20 10 all of the circuits 4, 5 and 6 may feed the fault. Here again the restraint is dependent on the sum of the effects on the windings 17, 18, 19. Under these conditions, however, the input and output currents of the transformer 25 10 are not balanced and the points 23 and 24 differ more or less in potential dependent on the severity of the fault. The difference between the input and output currents now becomes equal to the sum of the circuit currents. 30 This appears in the operating winding 16 whence it is divided among the restraining windings 17, 18, 19 but because of the preponderance of turns in the operating winding the operating effect exceeds the restraining effect. Consequently the relay 15 closes 35 the circuit of the auxiliary relay 87 and thereby effects the operation of the circuit breakers 11, 12 and 13.

In the embodiment of my invention shown 40 in Fig. 2 four inductively related circuits 4, 5, 6 and 38 are shown coupled through the power transformer 10' having windings 7, 8, 9 and 39. With this arrangement assuming that the circuit 38 may also supply power, the 45 protective relay 15 which is schematically illustrated, is provided with an additional restraining winding 40 connected to be energized in accordance with the current in the circuit 38 through a current transformer 41 and a suitable auto-transformer 42. The 50 operation of this modification of my invention will be obvious on reference to the description of Fig. 1 as it is merely an extension of the arrangement shown in Fig. 1 to 55 four circuits instead of three. If the circuit 38 is not connected to a source or to any means which could supply current even temporarily, it is unnecessary to supply the extra winding 40, the restraining effect due to the current 60 of the circuit 38 being obtained by arranging for one of the restraining windings 17, 18, 19 to be energized by this current.

In the embodiment of my invention shown 65 in Fig. 3 the circuits 4, 5 and 6 are conductively related and may form for example the

branches of a bus bar system it being assumed that any two of these circuits are arranged to supply the other. With this arrangement, of course, the auto-transformers may be omitted. Otherwise the arrangement, although schematically indicated in single phase diagram for clearness, is fundamentally identical with the arrangement shown in Fig. 1 and operates in the same manner.

While I have shown and described my invention in considerable detail I do not desire to be limited to the exact arrangements shown, but seek to cover in the appended claims all those modifications that fall within the true spirit and scope of my invention.

What I claim as new and desire to secure by Letters Patent of the United States, is:—

1. In combination, three or more electric circuits of which any two of at least three are arranged to supply the rest, and means for controlling said circuits including a relay having a movable member, an operating winding connected to be energized in accordance with the difference between the input and output currents of said circuits and restraining windings respectively connected to be energized in accordance with the currents of said circuits and arranged to exert cumulative effects dependent on only the magnitudes of the currents.

2. In combination, three or more electric circuits of which any two of at least three are arranged to supply the rest, and means for controlling one of said circuits including an electroresponsive device subject to an operating effect dependent on the difference between the input and output currents of said circuits and to cumulative restraining effects dependent on only the magnitudes of the circuit currents.

3. In combination, three or more electric circuits of which any two of at least three are arranged to supply the rest, and means for controlling one of said circuits including an electroresponsive device having means connected and arranged to produce an effect dependent on the difference between the input and output currents of said circuits and a plurality of opposing means respectively connected to be energized in accordance with the circuit currents and arranged to act cumulatively independently of the relative directions of the currents.

4. In combination, three electric circuits of which any two are arranged to supply the rest, and means for controlling one of said circuits including a relay having a movable member and operating means therefor including torque exerting means connected and arranged to exert a torque dependent on the difference between the input and output currents of the circuits and an opposing torque exerting means for each circuit connected to be energized in accordance with the current of the associated circuit, said ele- 130

ments being arranged to exert cumulative torques on said member dependent on only the magnitudes of the currents.

5. In combination, a power transformer having three or more mutually inductively related windings of which any two of at least three are arranged to supply the rest, and means for controlling the circuit of one of said windings including a relay having a movable member, means for operating said member arranged to be energized in accordance with the difference between the input and output currents of said windings and means associated with each winding and arranged to exert on said member cumulative restraints dependent on only the magnitudes of the currents in the respective windings.
6. In combination, three or more electric circuits of which any two of at least three are arranged to supply the rest, means for controlling one of said circuits, including an electroresponsive device connected and arranged to be controlled in accordance with the difference between two effects respectively dependent on $(I_1^2 + I_2^2 + \dots + I_n^2)$ and $(I_s - I_t)^2$ where $I_1, I_2, \dots, I_n$ represent the currents in the respective circuits, n being the number of circuits I_s and I_t represent respectively the sums of the currents supplied by and taken from said circuits.
7. In combination, three or more inductively related circuits of which any two of at least three are arranged to supply the rest, differential relay means for controlling said circuits including an operating winding connected to be energized in accordance with the difference between the input and output currents of the circuits, a plurality of restraining windings respectively connected to be energized in accordance with the circuit cur-
- rents and arranged to exert cumulative effects dependent on only the magnitudes of the currents, and interrupting means in one of said circuits arranged to be actuated in response to the operation of said relay when the ratio between the effects exerted by the operating and restraining windings exceeds a predetermined value.
8. In combination, three or more electric circuits of which any two of at least three are arranged to supply the rest, means for controlling said circuits including an electroresponsive device subject to an operating effect dependent on the difference between the input and output currents of said circuits and to cumulative restraining effects dependent on only the magnitudes of the circuit currents, and circuit interrupting means in one of said circuits arranged to be operated when the ratio between the operating and the restraining effects exceeds a predetermined value.
9. In combination, three or more electric power circuits of which any two of at least three are arranged to supply the rest, and means for controlling one of said circuits including a relay having an operating winding and a plurality of restraining windings and a circulating current protective circuit including said restraining windings respectively connected in series relation with said power circuits and to a common point, said operating winding being connected between said common point and a point in said protective circuit normally at the same potential.

In witness whereof, I have hereunto set my hand this 26th day of June, 1928.

RICHARD E. CORDRAY
